UNITED STATES PATENT OFFICE.

JOHN L. SCHULTZ, OF PHILADELPHIA, PENNSYLVANIA, ASSIGNOR TO AMERICAN ENGINEERING COMPANY, OF PHILADELPHIA, PENNSYLVANIA, A CORPORATION OF PENNSYLVANIA.

PROTECTIVE CURTAIN FOR FURNACES.

Application filed July 3, 1923. Serial No. 649,237.

One object of my invention is to provide a moving curtain for use in furnaces, where ordinarily there would be a formation of clinker adhering to the furnace lining, and 5 the invention more especially contemplates a traveling curtain made of metal sections positioned to replace such portions of the lining as would commonly be attacked or engaged by the clinker. The invention further 10 contemplates a construction in which the curtain sections successively enter the zone of high temperatures where they remain for a limited time only, and then move out of said zone so as to be permitted to 15 cool.

Another object of my invention is to provide a novel form of wall for the ash pocket or ash discharge end of a furnace, of such construction as to constantly present to the 20 heated fuel and ash, relatively cool sections and thereafter remove these when they have become heated, to allow them to cool.

I also desire to provide a furnace with a curtain-like wall presenting to the ash or 25 clinker relatively cool moving sections tending to break up clinkers as well as prevent their adherence.

The invention also includes novel means for supporting, moving and cooling the 30 sections of a furnace curtain wall.

A further object of my invention is to provide a furnace with a wall structure so constructed and positioned as to facilitate the movement of the ash toward the place of 35 discharge thereof and the invention also is designed to provide a traveling curtain formed of sections constructed to receive and carry water as they move into and through the zone of high temperature with 40 a view to preventing their being objectionably heated before they pass out of said zone.

These objects and other advantageous 45 ends I attain as hereinafter set forth, reference being had to the accompanying drawings, in which,

Fig. 1 is a vertical section of a portion of a furnace showing my invention as applied thereto;

Fig. 2 is an elevation, partially diagrammatic, of certain of the structures shown in Fig. 1;

Figs. 3 and 4 are respectively front and end elevations of one of the curtain sec-

tions of my invention and certain of the 55 links associated therewith Fig. 4 showing a part in section;

Fig. 5 is a vertical section similar to that of Fig. 1, showing a modified form of my invention as applied to the ash pocket of an 60 inclined underfeed stoker, portions of which are indicated diagrammatically;

Figs. 6 and 7 are respectively front and end elevations, showing the detail construction of the curtain sections of that form of 65 the invention shown in Fig. 5.

Fig. 8 is a vertical section similar to those of Figs 1 and 5, illustrating another modified form of the invention; and

Fig. 9 is a front elevation of a portion of 70 the structure shown in Fig. 8 with certain parts broken away.

In Figs. 1 to 4 inclusive of the above drawings, 1 represents a portion of the brick or concrete setting of a furnace having my invention applied to that portion thereof in and adjacent the ash discharge part of the furnace. The latter in the case shown, includes an ash pocket 2, in the bottom of which are placed ash crushing rolls, of which one is indicated at 3, there being a series of plates of which one is indicated at 4, pivotally hung on brackets 5 supported in any suitable manner from the setting 1, and extending upwardly for a short distance above the crusher rolls. Above the plates 4 and brackets 5, the setting 1 is overhung, being provided with a top plate 6 extending horizontally above the space immediately over said brackets 5 and having horizontal beams or 90 girders 7 and 8 mounted on or adjacent the substantially vertical face of the recess under said plate 6, with which they are parallel.

The girder 7 serves to support a series of 95 projecting bearing brackets 9, in which is journaled an idler shaft 10, while the beam 8 similarly supports a series of bearing brackets 11 carrying a power-driven shaft 12. These two shafts 10 and 12 are parallel 100 and extend parallel with the ash pocket 2, each having mounted upon it a series of pairs of sprocket wheels, indicated respectively at 13 and 14. The sprocket wheels of each two pairs serve to support two parallel endless chains, each consisting of a series of links 15—16 pivotally connected by pintles 17.

In this form of my invention, the links 15 are made in the form of flat, elongated plates and pairs of them are alternated with the single links 16, each of which has projecting laterally from it a lug 18 formed with an opening for the reception of a bolt 19. The curtain proper is made up of a series of transversely extending horizontal plate sections 20 each connected at its ends 10 by the bolts 19 to a pair of the links 16, the width of said plates being such that they present to the furnace a substantially flat face extending from the upper edge of the plates 4 to the front edge of the top plate 6, which is downwardly flanged as indicated at 21.

That face of each section 20 which is exposed to the heat of the furnace is substantially flat, except at its lower edge where 20 it is provided with a horizontal, outwardly projecting rib 22. Its rear or inner face has its lower portion formed to provide a trough or container 23 designed to receive water delivered from a supply pipe 24 extending transversely of the furnace immediately under the top plate 6 and having outlet openings 25, in the present instance so positioned as to direct streams of water against the inner surface of the flange 21, from which said water is free to fall over the plate sections 20 and collect in their troughs 23.

As will be evident from Fig. 2, any suitable or desired number of series of endless curtain sections or curtains may be provided and supported by the shafts 10 and 12, of which the latter is preferably driven by power from any suitable source, so that the plates 20 of all the series travel downwardly from under the water supply pipe 24 and flange 21. The flat faces of said plates are thus successively exposed to the hot gases and thereafter to the ashes and clinkers in the pocket 2. Under these conditions, it is evident that each of the sections successively enters the zone of high temperature in the furnace and by reason of its movement, makes it impossible for clinker or ash to collect upon it. At the same time the downward movement of the various sections constituting the exposed run of my endless curtain tends to break or crush the clinkers, as well as to facilitate their movement toward the crushing roll 3 or other discharge point or agency of the ash pocket. While so exposed to the heat of the burning fuel in the furnace and hot ash and clinkers, the sections 20 of the upright exposed face of the curtain become more or less heated but by reason of their movement, ultimately pass out of the ash pocket into the rear of the chamber or recess in which they are mounted, where as the protected run of the curtain they travel upwardly so that they have ample time to

cool before they are again exposed to the furnace heat. The water supplied from the pipe 24 not only tends to further cool the sections of the curtain, but also serves to keep them cool by collecting in their troughs 70 23, from which its evaporation still further tends to reduce the temperature of the sections.

In that form of my invention shown in Fig. 5, I have illustrated a slightly modified 75 form of protective curtain and have shown this as applied to the ash pocket 2^a of an inclined underfeed stoker, certain of whose tuyères are indicated at 30. These tuyères are arranged in stepped form and below them are customarily mounted stepped structures 31, having beneath them a rearwardly inclined face plate 32 defining one side of the upper part of the ash pocket. Below this structure 32 is a series of vertical plates 33 pivotally hung from brackets 34 in positions substantially opposite the plates 4 on the rear side of the pocket 2^a, whose bottom, in this instance is provided by a pair of crushing rolls 3 and 3^a. 90

In this case each chain is made up wholly of similar links 16^a so proportioned that the lower edge of each of the plates 20^a extends over the top edge of the plate next below it, in that part of the curtain exposed to the hot gases and ash in the furnace. The plates constituting the curtain sections are preferably wedge-shaped in section with their thinner edges at the top in the exposed face of the curtain and the water supply 100 pipe 24 is provided in such position as to deliver against the downwardly extending flange 21 of the top plate 6, from whence the water falls on the plate sections and links as these move over the top sprockets 105 13 and while they are moving downwardly. In this case the troughs are omitted.

In that modification of my invention shown in Figs. 8 and 9, the plates constituting the curtain sections have substantially the same construction as shown in Fig. 6, but in this case they occupy positions the reverse of those previously described,—that is to say, they are so mounted on the links 16^b that the lower and relatively thin 110 edge of each plate extends under the relatively thick edge of the plate next below it in that portion which is exposed to the ash and clinkers. 115

It will be noted that each of the plates 120 is longitudinally slotted for the reception of the bolts 19 so as to facilitate its mounting or replacement when this may be necessary. While my invention is particularly valuable when so mounted as to constitute 125 one of the walls of the ash pocket of a stoker, it may if desired be used to replace any portion of a furnace wall at the back or sides thereof, for example where there is a possibility or a likelihood of clinker, 130

ash or other material in highly heated condition attacking or collecting on said wall. In any case the endless curtain is operated to successively present to the heated zone 5 of the furnace, relatively cool sections and to successively remove and permit the sections to cool after they have been heated.

I claim:

1. The combination in a furnace of a movable curtain structure positioned to constitute a portion of the furnace lining; and means for cooling said curtain structure.
2. The combination in a furnace of a wall; an endless traveling curtain mounted adjacent said wall to constitute a portion of the furnace lining; and means for supplying a cooling medium to said curtain.
3. In a furnace, the combination with a furnace lining; of an endless movable sectional curtain constituting at least one portion of said lining; and means for supplying a cooling agent to said curtain, at least one of the sections of said curtain being formed to retain said cooling agent.
4. The combination in a furnace of an endless sectional curtain forming part of the furnace wall and having two runs, of which one is exposed to the heat of the furnace and the other is protected therefrom; and means for supplying a cooling medium to said curtain at the beginning of one of said runs.
5. In a furnace, the combination with an ash-receiving portion; of an endless traveling curtain formed in sections and adapted to constitute a portion of the furnace lining; means for moving the curtain to cause its sections to move alternately into and out of the ash-receiving portion; and means for supplying a cooling agent to said curtain, certain of said curtain sections being formed to hold said cooling agent.
6. In a furnace, the combination with a furnace lining; an endless sectional curtain constituting at least one portion thereof, certain of the sections of said curtain having opposite sides respectively adapted to be exposed to the heat of the furnace and to serve as receptacles for a cooling agent.
7. In a furnace, the combination with a furnace wall having a recess facing a heated zone of said furnace; of an endless sectional curtain so mounted in said recess as to present an approximately flat upright surface to solid material in said heated zone; means for so moving said curtain that the sections thereof are successively exposed to said heated material and thereafter permitted to cool in said recess; and means whereby said curtain may be further cooled.
8. In a furnace, a chamber, one wall of which is provided with a recess adapted to enlarge said chamber; a movable endless curtain structure positioned in said recess to constitute a portion of the furnace lining; means for moving said curtain; and means

for supplying cooling fluid to said structure.

9. The combination in a furnace of a movable curtain structure positioned to form a portion of the furnace lining and made of an endless series of sections including containers; means for supplying a fluid to the containers of said sections; and means for so moving the sections as to bring them successively into the heated portion of the furnace and thereafter to move them out of the same to permit them to cool.

10. In a furnace, the combination with a furnace lining; of sprocket wheels mounted one above the other adjacent to said furnace lining; chains extending approximately vertically between pairs of said sprocket wheels; horizontally extending plate sections detachably secured to said chains and arranged to form a curtain having an upright, approximately continuous face exposed to the material in the furnace; the curtain constituting one portion of said lining; and means for turning the sprocket wheels to successively expose relatively cool plate sections to the interior of the furnace.

11. The combination in a furnace of sprocket wheels mounted one above the other adjacent the furnace wall; chains extending approximately vertically between pairs of the sprocket wheels; horizontally extending plate sections mounted on the chains and arranged to constitute a curtain having an upright, approximately continuous face exposed to the material in the furnace; means for turning the sprocket wheels to successively expose relatively cool plate sections to the interior of the furnace; and means for supplying a cooling agent to those sections exposed to the furnace.

12. The combination in a furnace of a wall; a plate mounted therein having a downwardly projecting flange exposed to the furnace; approximately vertically extending chains mounted under said plate; horizontally extending metallic curtain sections mounted on said chains in an endless series and positioned to present an upright approximately flat face to the heated material in the furnace, certain of the sections being extended in a protected run between said face and the furnace wall; with means for directing a cooling agent against the flange of the plate above the curtain to permit said agent to fall upon and cool the exposed sections.

13. In a furnace, the combination with an ash pocket having means for removing ashes from its lower portion; of a traveling sectional, endless curtain having a run positioned to constitute one side of said ash pocket; means for moving the curtain to cause the sections in said run to move downwardly; and means for supplying a cooling agent to the sections in the exposed run.

14. The combination in a furnace of an

- 4
- endless curtain constituting a portion of the lining thereof and made up of sections of which certain are supported to constitute an approximately flat upright face exposed to the heated material in the furnace, each of the sections having a horizontally extended portion projecting into the furnace; and means for moving the curtain to cause the sections exposed to the heat of the furnace to move downwardly.
15. In combination, a furnace wall having a horizontal plate provided with a depending exposed flange; a pair of shafts; a supporting beam for said plate provided with a plurality of brackets having bearings for one of said pair of shafts; a second beam having a bearing for the other of said
- shafts; a curtain mounted on said shafts so as to protect the adjacent furnace wall; and means for discharging a cooling fluid 20 against said depending flange, the latter being so positioned as to cause said fluid to fall on said curtain.
16. In a furnace, the combination with a furnace lining facing a heated zone thereof; of an endless sectional curtain spaced from said lining so as to protect the same but also constituting one portion of said lining; and means for so moving said curtain that the sections thereof are successively moved from immediate proximity to said furnace lining into positions exposed to said heated zone.

JOHN L. SCHULTZ.
